PENCIL

John A. Vierling, St. Paul, Minn., assignor to
 Brown & Bigelow, St. Paul, Minn., a corpora-
 tion of Minnesota

Application October 16, 1950, Serial No. 190,355

5 Claims. (Cl. 120—17)

1

My invention relates to a pencil wherein the lead may be propelled and retracted by turning the tip of the pencil, or the barrel when the tip is held stationary, to cause the writing lead to be projected or retracted into the barrel. The lead may also be projected out of the writing end of the pencil by pressing downwardly on the tip of the pencil out of which the writing lead ordinarily projects. This operation causes a portion of the barrel to telescope against the action of an internal spring, and when the downward pressure on the writing tip is released, the action of an internal clutch rotates the lead propelling mechanism to project a predetermined amount of lead out of the writing end of the pencil.

My pencil is designed to combine the ordinary lead propelling and retracting mechanism which is anchored in the forward end of the pencil with a clutch means, which causes the propelling mechanism to be rotated on the upward movement of the clutch within the barrel. This combination of elements performs a function of forcing the writing lead out of the tip of the pencil a degree at a time each time the pencil is pressed downward on a solid surface and then released.

The writing lead is supported in the propelling and retracting mechanism in a lead socket which receives the rear end of the lead to hold it firmly in the inner tube of the propelling and retracting mechanism, whereas the socket which holds the lead is adapted to be driven by a spiral member extending around the center tube which holds the lead and the lead socket. A tooth-like member extends from the rear end of the socket to engage in the spiral groove which forms the propelling and retracting member of the mechanism of the pencil. The propelling mechanism is also provided with a central ejecting rod which extends through the socket, which holds the lead, but in an operative position is positioned rearwardly from the front edge of the socket to permit the lead to extend into the socket and bear against the ejecting rod as a shoulder. When the propelling mechanism is operated to its forward limit in projecting the writing lead, the lead ejecting rod is driven through the socket forcing out the stub end of the lead which ordinarily would remain in the socket, which is the unused portion of the writing lead. This mechanism for propelling and retracting the lead is not in itself new, and I have illustrated the same in the drawings diagrammatically. However, I have combined this mechanism with a

2

clutch means for operating the same to cause the writing lead to be driven out of the writing tip of the pencil by merely pressing down on the writing end of the pencil, which telescopes a portion of the barrel and causes my clutch mechanism to eject a predetermined amount of lead out of the writing tip of the pencil when the downward pressure is relieved and the barrel expands to its normal size.

- 10 The manner in which I accomplished the automatic operation of ejecting the lead by pressing down on the writing tip is obtained by extending the center tube of the lead ejecting and retracting means rearward in the pencil and 15 mounting or forming a spiral groove on the center tube which supports the clutch and on which the same slides in operating the pencil to eject a portion of the lead. One portion of my clutch is adapted to be fixed to a portion of the 20 pencil barrel and moved with the same. The other portion of the clutch floats around the spiral groove member and over the center tube and is formed with a series of teeth which are 25 adapted to engage the teeth on the stationary or fixed portion of the clutch. Downward pressure on the pencil, which compresses the spring within the same, causes the floating portion of the clutch to rotate and ride over the teeth of the stationary portion. When the downward pressure is released, the floating portion of the 30 clutch is held against turning, whereupon the lug within the floating portion which engages the spiral groove, carried by the center tube, causes the center tube to be rotated in the backward movement of the clutch, and thereby eject 35 the lead out of the writing tip, a predetermined amount.

In this manner my simple clutch carried by the rear end of the center tube of the propelling and retracting means operates this mechanism 40 to eject a portion of writing lead in a very simple and positive manner, without clutching jaws engaging the writing lead to force the same out of the writing tip.

Heretofore mechanical pencils for ejecting the lead have been made, however, in most of these types of pencil the clutch mechanism engages directly against the writing lead, and such pencils do not operate satisfactorily because usually 50 there is some slippage of the clutch on the writing lead or the writing lead may be worn away or not entirely true to size and form, and then the ejecting clutch will fail to operate. I have overcome this type of lead ejecting means in a simple and a positive manner so as to drive the

lead out of the writing tip a degree at a time, whenever pressure is exerted against the writing end of the lead or tip of the pencil.

Furthermore, I have provided a pencil with the combined function of permitting the lead to be propelled or retracted by turning the writing tip or barrel of the pencil, if it is desired, or the lead may be ejected without turning the tip or the barrel but by simply pressing down on the writing tip of the pencil to operate the automatic clutch within the casing. This provides a selector type of pencil with a positive lead feeding clutch means which does not grip the lead itself to propel it.

In the drawings forming part of this specification:

Figure 1 is an enlarged longitudinal section of my pencil in expanded form.

Figure 2 is a similar section to Figure 1 with the pencil barrel compressed and telescoped together.

Figure 3 is an enlarged detail of my clutch, which is mounted on the center tube.

Figure 4 is a section on the line 4—4 of Figure 3 of a clutch element.

Figure 5 is another form of my pencil showing a different construction of the barrel.

Figure 6 is a perspective view of the front end of one of the tubes used in my pencil shown in Figure 5.

The drawings illustrate the pencil A in Figures 1 and 2. Figure 1 illustrates the pencil partially in section with some of the other parts in full lines. The writing tip 10 is rotatably mounted on the longitudinally grooved collar 12 which is anchored in the forward end 11 of the pencil. The portion 11 of the pencil A may be formed of plastic or any other suitable non-metallic material, and ordinarily forms the gripping end for one's fingers in holding the pencil.

The lead holding and propelling and retracting means B is old in the art and is shown diagrammatically in Figure 2 and includes the writing tip 10, the collar 12, the spirally wound member 13 which forms the helical slot 14. The member 13 is fixed to the collar 12 and extends down into the same in its helical form to provide the track for operating the lug 15 formed on the rear end of the elongated lead socket which is positioned within the slotted tube 15' and the lug 16 formed on the rear end of the plunger rod 16' which projects into the lead socket which travels longitudinally in that portion of the center tube 17 which extends through the spirally wound member 13. The tube 15' passes through the collar 12 and is connected to the tip 10. The lugs 15 and 16 project outwardly through the slot of the tube 15' and into the helical slot 14.

The lead propelling and retracting mechanism B may be operated by turning the rotatable tip 10 while the barrel portion 11 is held stationary or by holding the tip portion 10 stationary and turning the barrel portion 11. In this manner the lead in the propelling mechanism B is caused to move out of or be retracted back into the writing tip 10 and into the center tube 17 of this mechanism. As the tip 10 is rotated so is the slotted tube 15' which forces the lugs 15 and 16 to follow the spiral slot 14 to retract or project the elongated socket within the slotted tube member 15'.

In my pencil A I have extended the center tube 17 which is an extension of the lower tube portion 15' up into the pencil, as illustrated in Figures 1 and 2. The inner portion of the center

tube 17 is enlarged in diameter at 17' to provide a receptacle for supporting extra leads in the pencil A so as to hold the extra leads 18 positioned in the core of the pencil.

The outer casing portion 19 of the pencil A is adapted to slide on the portion 11 so that the portion 11 will telescope into the casing portion 19 when the pencil A is compressed together.

The inner end of the member 11 is formed square or angular at 20 and is adapted to be engaged by the collar 21, which is fixed to the casing 19. When the casing 19 is moved longitudinally, the square portion 20 holds the pencil barrel against turning so that the members 11 and 19 of the pencil remain in line and are held against rotation during the telescoping of the pencil. The movement of the casing 19 over the member 11 is illustrated in Figure 2 which shows the forward end of the casing 19 moved down over a considerable portion of the part 11 during the compression of the pencil A.

The portions 11 and 20 are integral and are formed with a further extension 22, which provides a guide for the center tube 17 and the portion 17'. A shoulder 23 is formed between the portions 20 and 22 and against this shoulder the washer 24 engages providing for a support for one end of the coil spring 25 which extends around the portion 22 and the upper end of which engages against the shoulder 26 formed in the clutch member 27. The clutch member 27 is rigidly fixed to the casing 19 and is adapted to move with the same in the longitudinal movement of the casing member 19. The movement of the clutch portion 27 is over the outside of the spirally grooved sleeve 28, which is fixed to the upper portion 17' of the center tube, so that any rotation of the center tube 17 and the portion 17' will also rotate the member 23 or the member 28 when rotated will rotate the center tube 17 and operate the lead propelling mechanism B.

Directly above the fixed clutch portion 27 I provide a floating clutch portion 29 in the form of a sleeve collar and which is formed with an internal lug 30 adapted to engage in the spiral groove 31 of the sleeve member 28.

Operating mechanism B is assembled in the pencil A by inserting the same into the open end of the casing member 19 at the front of the pencil and securing the same against the tension of the coil spring 25 by upsetting the inner end of the center tube 17 over the conical inner surface of the collar 32 at the point 33.

I provide a tubular eraser supporting member 34, which is formed with inner shoulders 35, against which the collar 32 engages when the spring 25 is expanded, as illustrated in Figure 1, and which is adapted to support the eraser 36 which closes the chamber for the extra leads 18 at the top of the member 34.

I also provide an eraser cap 37, which telescopes over the tubular member 34 of the pencil barrel.

In operating the pencil A to eject a lead by pressing the writing tip 38 against a fixed surface, the pencil is held upright and pressure is exerted against the tip 38. This causes the casing 19 of the pencil A to telescope over the gripping end 11 of the pencil into the position illustrated in Figure 2. This compresses the spring 25 and moves the clutch members 27 and 29 longitudinally of the center tube 17 into the position illustrated in Figure 2. The clutch member 27 is fixed to the casing 19 so that it will move longitudinally but will not rotate while the

clutch member 29 floats over the sleeve 28. The lug 30 engages in the helical slot 31 causing the floating clutch member 29 to rotate in relation to the clutch member 27. This operation causes the teeth 39 on the clutch member 29 to ratchet over the teeth 40 on the fixed clutch member 27. This operation advances the floating clutch 29 into position to engage the helical slot 31 in an advanced position so that when the downward pressure on the pencil barrel is released the spring 25 will return the clutch members 27 and 29 to the position illustrated in Figure 1, and the clutch member 29 through its lug 30 engaging in the helical slot 31 will cause the center tube 17 to rotate sufficiently to push a lead 18 a predetermined distance out of the end 38 of the pencil tip 10.

It will be apparent that while the fixed clutch member 27 travels with the movement of the casing member 19 of the pencil A, the floating clutch member 29 is engaged by the member 34 and with the aid of gravity travels to a downward position said clutch 29 being rotated by the helical slot 31 so as to advance the clutch made up of the members 27 and 29 into a position to cause the center tube 17 to rotate and drive a writing lead 18 out into writing position.

Therefore, in operating my pencil A all that is necessary for the operator to do when the lead 18 wears off or breaks is to press down on the barrel of the pencil, causing the clutch members 27 and 29 to be positioned in a manner to rotate the center tube of the lead propelling and retracting mechanism B, which ejects the lead a degree or predetermined amount at a time.

It will also be apparent that in the back stroke or movement of the clutch mechanism 27 and 29, the member 29 is held against rotation by reason of the engaging of the teeth 39 and 40, which prevent the member 29 from rotating when it moves longitudinally backward.

The hollow, enlarged end 17' of the center tube 17 provides a storage for extra leads 18 as heretofore stated, and the collar 32 acts to guide the leads 18 into the center tube 17.

It will be apparent that the construction of the barrel of the pencil A in Figures 1 and 2 provides the telescoping of the portion 19 over the gripping end 11 of the pencil, and to illustrate another form of the barrel, I have shown Figure 5 which places the telescoping portions at the rear of the pencil. In this form of the pencil shown in Figure 5 the casing portion 19' engages against the shoulder 41, and the open end of the tube 19' is at the rear of the pencil. Thus the tube 19' will telescope over the tube 42, and the tube 42 will support the clutch member 27 to which it is fixed. The clutch member 29 floats about and adjacent to the clutch member 27, as heretofore described, and the sleeve 28 causes the clutch member 29 to operate to rotate lead propelling mechanism B, which is attached to the tip 18 in the same manner as illustrated in Figure 2.

The forward, inner end of the tube 42 is formed with a square portion 43 which engages the square portion 20' of the end 11' of the pencil. Thus the tube 42 is held against rotation and in line with the portion 11' of the pencil, and when the pencil is compressed to operate the clutch members 27 and 29 the square end 43 rides along longitudinally on the squared portion 20 of the inner end of the member 11'.

In the pencil illustrated in Figure 5, I have provided an eraser cap 44 which covers the eraser

36. Enlarged end 17' of the center tube 17 supports the extra leads.

The construction of the pencil A illustrated in Figure 5 may be the preferred form of my pencil so that the telescoping of the barrel is positioned at the rear of the pencil rather than at the forward end where the pencil is gripped on the portion 11 when held in writing. The portion 11 of my pencil may be made of plastic or any other non-metallic material so as to give a soft gripping material for the fingers, and the operation is extremely simple, yet positive, to move the writing lead 18 into writing position.

In Figure 2 I have shown a fixed surface 45 against which the tip 38 of the barrel A is being pressed in the direction of the arrow, while the pencil A is held in a vertical position.

A feature of my pencil which increases its utility and makes it more desirable for the operator is that the lead 18 can be propelled and retracted by holding the barrel and rotating the tip or vice versa. The lead propelling mechanism B is easy to fill after the stub end of the lead has been ejected by the plunger rod 16'. It is only necessary to engage the tip 10 and rotate the barrel to carry the plunger rod 16' in a retracted position, whereupon the lead can be inserted into the position 18 and forced into the socket of the lead holding means in the mechanism B. Thereafter the pencil is ready to operate, either by holding the barrel 11 and rotating the tip end 10, or by holding the tip 10 and rotating the barrel 11, or by pressing downward on the end 38.

35 My pencil has the advantage of quick operation for ejecting lead by merely pressing down against the end 38 while the barrel of the pencil is held vertical to permit the floating clutch portion 29 to operate and be set in position to grip the clutch portion 27 and rotate the tube 17, which operates the mechanism B, to push the lead 18 out of the writing tip. Should the user of my pencil A desire to rotate the tip to propel or retract the lead, he may readily do so, as herein set forth. The advantage of this combined operation is apparent because it is often desirable to withdraw the lead into the pencil when it is not desired for use, and while the operator may eject the lead by pressing down on the barrel, it is only necessary to engage the tip and rotate the barrel to retract the lead into the casing of the pencil, thus protecting the user against the projecting lead when the pencil is inserted in the operator's pocket.

55 A further advantage of my lead propelling mechanism resides in the fact that to propel the lead by the clutch mechanism 27 and 29 the lead is never engaged by any clutch jaws like has been used in old forms of clutch propelling pencils, but the lead is held protected within the inner tube 17 and rests in the socket in the mechanism B, and to propel a lead the mechanism B is operated by rotating the lead center tube 17, which positions the lead forward a degree at a time on the backware movement of the clutch members 27 and 29. Thus the operator is always assured that whenever he presses on the tip of the pencil a portion of the lead will be ejected, if there is any lead in the mechanism B. This is an extremely important feature of my pencil. It insures the user of my pencil of positive operation either by rotating the parts of the mechanism B or by pressing down on the writing tip of the pencil causing the clutch means to eject the lead.

I claim:

1. A mechanical pencil having a lead projecting and retracting means comprising concentric, relatively rotatable, tubular parts and lead projecting and retracting members shiftable longitudinally by the relative rotation of said parts and including a barrel for concealing said projecting and retracting means, the rear end of said projecting means extending into said barrel, a portion of said barrel being adapted to telescope, a coil spring supported in said barrel, a lead operating clutch mounted in said barrel and extending around said rearwardly projecting portion of said propelling means, and a sleeve having a spiral groove carried by one of said relatively rotatable tubular parts of said projecting means over which said clutch is adapted to operate, said spring holding said clutch in rearward position and expanding said barrel to normal position, said clutch including a fixed clutch member secured to a wall portion of said barrel and having ratchet teeth formed thereon and a floating clutch member having ratchet teeth formed thereon and a lug for engaging said spiral groove, said clutch means being adapted to rotate one of said tubular parts of said projecting means relative to the other to operate said lead projecting means when said barrel is telescoped by pressing on the writing end thereof.

2. In a mechanical pencil, a casing, a partial forward barrel portion on which said casing telescopes, a rotatable lead holding projector and retractor mechanism secured to said barrel portion including concentric, relatively rotatable, tubular parts and lead projecting and retracting members shiftable longitudinally by the relative rotation of said parts and including a sleeve secured to one of said relatively rotatable, tubular parts of said projector mechanism having a spiral groove formed therein, a floating, toothed clutch having a lug engageable in said spiral groove element, a fixed toothed clutch member secured to the inner surface of said casing, and spring means holding said casing and said clutch members in a rearward position with respect to said lead holding mechanism, said teeth of said fixed clutch adapted to ride over said teeth of said floating clutch when said casing is telescoped onto said partial barrel and engage said teeth of said floating clutch when said casing is released to a rearward position to rotate one of said tubular parts of said lead projector mechanism relative to the other and project a lead therefrom, a predetermined amount.

3. In a mechanical pencil, a casing, a rotatable projector-retractor lead holding mechanism comprising concentric, relatively rotatable, tubular parts and lead projecting and retracting members shiftable longitudinally by the relative rotation of said parts and including means for mounting said lead holding mechanism in said casing, a spiral sleeve mounted on the inner end

of one of said relatively rotatable, tubular parts of said lead holding mechanism, a fixed toothed clutch member secured to said casing, and a floating toothed clutch coacting with said fixed clutch member and having a lug formed thereon in engagement with said spiral sleeve to rotate one of said tubular parts of said mechanism relative to the other and project a lead therefrom when said casing is pushed downwardly with respect to said lead holder and released.

4. In a mechanical pencil, a casing, a lead holding projector-retractor mechanism mounted on said casing comprising concentric, relatively rotatable, tubular parts and lead projecting and retracting members shiftable longitudinally by the relative rotation of said parts and including a toothed clutch member secured to said casing, a floating toothed clutch member adapted to ride on and engage said toothed clutch member, a sleeve having a spiral formed thereon secured to the rear inner end of one of said relatively rotatable, tubular parts of said lead holding mechanism, and a lug formed on said floating clutch and in engagement with said spiral groove so that when said casing is pushed downwardly over a portion of said lead holding mechanism and released said clutch members rotate one of said tubular parts of said lead holding mechanism relative to the other and project a lead therefrom, a predetermined amount.

5. A mechanical pencil including a casing, a lead projecting and retracting means comprising concentric, relatively rotatable, tubular parts and lead projecting and retracting members shiftable longitudinally by the relative rotation of said parts and including a lead ejecting means for the stub of the writing lead, clutch means for operating said lead projecting and retracting means including a fixed clutch member connected to said casing having ratchet teeth formed thereon, a floating clutch member having ratchet teeth formed thereon adapted to engage with the teeth on said fixed clutch member, a sleeve having a spiral groove fixed to one of said relatively rotatable tubular parts of said lead projecting and retracting means, and a lug fixed to said floating clutch member and riding in said spiral groove whereby said clutch means is adapted to rotate one of said tubular parts of said means relative to the other to operate said lead projecting and retracting means to project the writing lead a degree at a time from the pencil.
